US00D609917S

(12) **United States Design Patent**
Benson et al.

(10) **Patent No.:** **US D609,917 S**
(45) **Date of Patent:** **** Feb. 16, 2010**

(54) **CLEANING TOOL**

(75) Inventors: **Shaelyn D. Benson**, St. Paul, MN (US); **Scott D. Gullicks**, Apple Valley, MN (US); **Lloyd S. Vasilakes**, Stillwater, MN (US); **Scott J. Tuman**, Woodbury, MN (US); **Byron E. Trotter**, St. Paul, MN (US); **Dana M. Vajen**, Minneapolis, MN (US); **Micah T. Somers**, Minneapolis, MN (US); **Brian M. Clemens**, Burnsville, MN (US)

(73) Assignee: **3M Innovative Properties Company**, St. Paul, MN (US)

(**) Term: **14 Years**

(21) Appl. No.: **29/334,623**

(22) Filed: **Mar. 30, 2009**

(51) LOC (9) Cl. **04-02**

(52) U.S. Cl. **D4/136; D32/35**

(58) **Field of Classification Search** **D32/35, D32/40, 45, 52; D4/116, 114, 121, 127, D4/130, 132-133, 136, 138, 119, 137, 118; 15/105.52, 107, 114, 118, 237, 142, 104.92, 15/21.1, 320-321, 323, 104.001, 186-188, 15/231; 401/146, 6, 268, 118, 123, 131, 401/28; D28/91.2, 51**
